AUTOMOBILE ORNAMENT

Roger J. Harris, P.O. Box 45684,
Dallas, Tex. 78235

Filed Feb. 18, 1972, Ser. No. 227,706

Term of patent 14 years

Int. Cl. D12—08

U.S. Cl. D12—190

FIG. 1 is a front elevational view of an automobile ornament showing my new design;

FIG. 2 is a rear elevational view thereof;

FIG. 3 is a top plan view;

FIG. 4 is a bottom plan view thereof.

The broken lines shown in FIGS. 1 and 2 are for illustrative purposes only.

I claim:

The ornamental design for an automobile ornament, substantially as shown and described.
